(57) **CLAIM**

The ornamental design for a speaker grill, as shown and described.

DESCRIPTION

FIG. 1 is a front elevation view of a speaker grill.

FIG. 2 is a top plan view thereof. The view of the opposing side is identical; and,

FIG. 3 is left side elevation view thereof. The view of the opposing side is identical.

The broken lines depict an environment of use and form no part of the claim.
